UNITED STATES PATENT OFFICE

2,087,886

SWITCHING DEVICE

Harrison J. L. Frank, Detroit, Mich.

Application March 16, 1935, Serial No. 11,430

6 Claims. (CL 200—114)

This application relates to switching devices and more particularly relates to switching devices of the character disclosed in the patents to Murray 1,158,534, November 2, 1915, and Frank 5 et al. 1,825,267, September 29, 1931.

The switching device here shown is of the accessible fuse safety type and includes a casing containing a switch of the carrier and base type, as shown in application Serial No. 750,492, filed 10 October 29, 1934, of which the instant application is a continuation in part; the switch includes a fuse carrier or head which can be reciprocated through a slot in the casing cover for switching by means of a handle formed on the 15 carrier and accessible from outside the cover of the casing of the switching device, the handle being manipulable to cause reciprocation of the carrier in a direct manner without the intervention of mechanical linkage between the handle and the carrier.

The principal object of the inventions of this application is to provide in a simplified, safely operable, compact, and economical form, and in conjunction with a switch of the character described above, an accessible fuse safety type switching device provided with means operable at the option of the user to provide all and more of the advantages of operation and construction provided by the switching devices of the aforementioned patents.

In order to attain such object, the switching device is provided with an optionally operable means which can be manipulated as desired so as to provide desired relations between the switch 35 parts themselves and between the switch parts and the casing.

The device here shown is intended to be useful as a substitute for the crank type externally operated accessible fuse safety switches now being 40 marketed, and for this reason care has been taken to provide, in the device here shown, all of the desirable attributes of the switches now being marketed, but in a simpler, more economical, and more readily and flexibly adjustable form.

45 For an understanding of the switching device here disclosed, reference may be had to the appended drawings and to the following detailed descriptive matter which relates to the same. In these drawings,

50 Fig. 1 is a cutaway front view of the switching device, with the main and branch circuit covers closed;

Fig. 2 is a similar view but with the main cover 55 of the device swung open to expose its interior;

Figs. 3 and 4 are views of a fuse carrier forming part of the switch proper of the device;

Fig. 5 is a cutaway front view of the switching device with the interlocking plate thereof disposed in a position A, where it does not operate 5 for interlock; in this view the branch circuit cover is shown swung open to expose the branch circuit connection block fuses;

Fig. 6 is a section as if on line 6—6 of Fig. 5;

Fig. 7 shows the extent of withdrawal of the 10 carrier when the interlocking plate is in non-operating position A, Fig. 5;

Fig. 8 shows the relation of the parts when the interlocking plate occupies position B wherein it permits normal switching action accompanied by exposure of the fuses of the carrier sufficient for inspection and removal, but preventing access to the live parts of the device even when the carrier is pulled out for fuse exposure;

Fig. 9 shows the extent of withdrawal of the 20 carrier when the interlocking plate is in position B, Fig. 8;

Fig. 10 shows the relation of the parts when the interlocking plate is in position C wherein it operates to permit withdrawal of the carrier 25 sufficient for normal switching action and to expose the fuses for inspection, but not sufficient to expose the fuses for removal, the live parts under these circumstances, even when the carrier is moved for fuse exposure, being inaccessible; 30

Fig. 11 shows the extent of withdrawal of the carrier when the interlocking plate is in position C, Fig. 10;

Fig. 12 shows the relation of the parts when the interlocking plate is in position D wherein 35 it operates to seal the entire device in status quo;

Fig. 13 is a section as if on line 13—13 of Fig. 12; and

Figs. 14—15 show a modified form of carrier interchangeable with the carrier of Figs. 3 and 40 4 in the switch of the device.

For an understanding of the drawings, reference should be had to the following detailed description of the parts therein shown.

The switching device includes a sheet metal 45 box 10, adapted to be mounted on a vertical wall W, Fig. 13, to which is hingedly attached at 11 a main cover 12 provided with an aperture 14 through which may pass a spring latch 15 secured to the box and formed for the reception 50 of a seal or padlock 16 whereby the main cover may be sealed or locked if desired.

Disposed within the box is a switch including a receptacle or base 17 having line and load contacts 18—18a disposed in slots 19 of the floor of 55

the base so as to be shielded at all times against accidental contact, but normally accessible when the fuse carrier 20 whose contacts 21 are adapted to engage the contacts 18-18a is not in position within the receptacle, the receptacle contacts being inaccessible against mischievous or malicious purposes when the carrier is partially or wholly associated with the receptacle or base. The carrier contacts operate to bridge the base contacts through main fuses "F" which may be of the plug type as in Figs. 3 and 4 or of the cartridge type, as in Figs. 14 and 15, it being observed that a plug fuse carrier may be substituted for or replaced by a cartridge fuse carrier with no difficulty whatever, inasmuch as the carriers, except for the fuses carried thereby, are similar.

For providing branch circuit connection, there are provided branch circuit blocks 22 whose terminals may be properly interconnected to the parts of the receptacle 17 through the branch fuses "f" and through the medium of parts 23, shown as straps but which may be meter coils, as will readily be understood. The control of the branch circuits supplied by the device is of course established through the use of carrier 20 with respect to the receptacle or base 17.

The main cover 12 is provided with a main slot 26 through which the carrier may be reciprocated for switching.

The main cover 12 is also provided with a supplementary opening 27 registering with the branch circuit fuses "f" through which these may be accessible for inspection or replacement, and masked by a masking plate 28 secured to the main cover; and for closing the supplementary opening there is provided a branch fuse cover 29 hinged to the main cover at 30 and provided with a handle 31; the cover 29 may have a latching lug 31a engaging in a notch 31b of the masking plate, as shown.

The main cover may have a small cover 32 hinged to it at 33 for covering the handle of the carrier 20 and protecting it against breakage, and cover 32 may be sealed or locked shut, as shown in Figs. 1 and 13, if desired, by the main cover seal 16 or by a separately operable seal or lock, passed through sealing lugs 33-34 registering with each other and, if desired, with latching lug 16 for the main cover. The provision of the cover 32, and the provision of its seals, may be left to the discretion of the manufacturer or user, as will readily be understood.

In order to attain the objects and advantages described earlier in this specification, interlocking means may be provided and such means as well as its operation will now be described.

Disposed behind the main cover 12 is an interlocking plate 40 mounted thereon by means of the pin and slot guide construction including slots 41 of the plate 40 receiving headed pins 42 of the main cover. The interlocking plate is shaped roughly in the form of a U, substantially as shown, and the opening or clearance between the legs and bight thereof is proportioned to the size of the main slot 26 of the main cover so as to cooperate therewith in a manner that will later be described.

For positioning the interlocking plate in one of its four positions A-B-C-D, as desired, the plate has an index slot 43 in its bight through which may be passed a pin 44 secured to the main cover and provided with a threaded shank (Fig. 6) for the reception of a nut 46 disposed within the casing and manipulable only when the

main cover is open, the nut when threaded down securing the interlocking plate against movement. The index slot 43 is provided with four enlargements referenced A, B, C, and D respectively, whose registration with the pin 44 defines positions A, B, C, and D of the interlocking plate, which positions determine the interlocking characteristics of the device.

It is observed that the carrier 20 is provided with L-shaped projections including lugs 47 and 48 which guide the carrier in its switching action by being received within receptacle slots 49, and in addition cooperate with parts of the interlocking plate for interlocking purposes.

Position A, Figures 5 and 7

When the interlocking plate is in the position shown in Fig. 5, namely position A, no part thereof restricts or restrains any movement of the carrier 20 or any movement of the branch fuse cover 29. Under such circumstances normal switching action is assured with the carrier being receivable in the receptacle in either one of two positions 180 degrees apart for circuit closing or circuit opening; and access to the branch circuit fuses is completely free. It is observed that when the interlocking plate is in position A, the live parts of the switch are always accessible for contact, even though they are shielded against accidental contact.

Position B, Figures 8 and 9

If it is desired to lock the carrier 20 against complete removal from the switching device and to debar access to the live parts even though normal switching action is not interfered with, the interlocking plate may be moved to position B, Figs. 8 and 9, where its portions 50 will register with lugs 47 of the carrier and prevent complete removal of the carrier from the receptacle without interfering with movement of the carrier sufficient for switching action. Accordingly, though the carrier may be manipulated for normal switching action and for inspection or removal of the main fuses, complete removal of the carrier from the device is prevented and access to the live parts is also prevented, assuming the main cover to be sealed or locked, as it usually is.

If desired, the main cover may be provided with springs 51 for cooperating with seats 52 of the carrier, whereby the carrier may be held in circuit open position, partially inserted in the receptacle. This provides a means whereby the carrier, though non-removable from the device, may be retained in circuit open position.

Position C, Figures 10 and 11

If it is desired to provide the optional operating characteristics provided by the parts when the interlocking plate is in position C, and in addition to prevent removal of the main fuses, the locking plate may be moved to position C, Figs. 10 and 11, so that its portions 50 will register with lugs 48 of the carrier and cut down the degree of movement of the carrier to such an extent that the main fuses may be exposed sufficient for inspection only but not sufficient for removal.

Position D, Figures 12 and 13

For sealing or locking the entire device, the interlocking plate may be moved to position D where its portions 54 will register with corners 55 of the body of the carrier to lock the same against withdrawal, in switch closing or switch open position, and where its ends 56 will pass

through slots of the masking plate 28 around the branch circuit blocks 22 to register with lugs 57 of the cover 29 and prevent opening of the latter.

5 Under such circumstances a single seal 16, passed through lug 15, will seal the entire device against access and in status quo.

It may be observed that the provision of a single seal through lugs 15 and 33-34 will also 10 seal all of the parts, regardless of the position of the interlocking plate.

Summary.

In order to summarize the novel features of 15 the device it is observed that the user of the device may at his option provide normal switching action with or without access to the live parts, and with or without access to the main fuses for renewal, and without interfering with 20 access to these fuses for inspection; that the main cover may be opened without requiring the carrier to be moved to switch "off" position; that the switch in part or in whole may 25 readily be locked or sealed in status quo; and that the same may be accomplished with a single seal at 15.

In other words, the device here shown may 30 be used as an "accessible fuse switch", or a "sealable fuse switch", or a plain "interlocked switch".

It is noted that the switch here shown possesses the important safety feature stressed in "externally operated switches" that the live 35 parts are shielded against accidental contact at all times when the main cover is closed, and that this feature is provided in a switch which is much more simple, economical, and compact than "externally operated switches" now known.

Now having described the device herein illustrated, reference should be had to the claims 40 which follow for a determination of the monopoly herein claimed.

I claim:

1. A switching device comprising a casing having 45 a cover provided with an opening and containing a switch base behind the opening, a switching head constructed and arranged to be movable through the opening towards and away from the base for switching action, and means comprising a movably mounted element manually and optionally movable into and out of a plurality of stopped and indexed positions, in 50 one of which it clears the head for permitting withdrawal and removal of the head from and movement and association of the head to the device from outside the same with the cover closed, and in another of which it cooperates with formations on the head for preventing separation of the head from the device with the cover closed while permitting it to be moved 55 towards and away from the base.

closed, and in another of which it cooperates with formations on the head for restraining withdrawal of the head from the base.

2. A switching device comprising a casing having 5 a cover provided with an opening and containing a switch base behind the opening, a switching head constructed and arranged to be movable through the opening towards and away from the base for switching action, and means comprising a movably mounted element manually and optionally movable into and out of a plurality of stopped and indexed positions, in 10 one of which it clears the head for permitting withdrawal and removal of the head from and movement and association of the head to the device from outside the same with the cover closed, and in another of which it cooperates with formations on the head for preventing separation of the head from the device with the cover closed while permitting it to be moved 15 towards and away from the base.

3. A switching device comprising a casing having 20 a cover provided with an opening and containing a switch base behind the opening, a switching head constructed and arranged to be 25 movable through the opening towards and away from the base for switching action, and means comprising a movably mounted element manually and optionally movable into and out of a 30 plurality of stopped and indexed positions, in one of which it clears the head for permitting withdrawal and removal of the head from and movement and association of the head to the device from outside the same with the cover 35 closed, and in another of which it cooperates with formations on the head for preventing separation of the head from the device with the cover closed while permitting it to be moved 40 towards and away from the base, and in another of which it cooperates with formations on the head for restraining withdrawal of the head from the base.

4. A construction of the character described 45 in claim 1 wherein the element is carried by and disposed below the cover and manipulable only when the cover is open.

5. A construction of the character described in 50 claim 2 wherein the element is carried by and disposed below the cover and manipulable only when the cover is open.

6. A construction of the character described in 55 claim 3 wherein the element is carried by and disposed below the cover and manipulable only when the cover is open.

HARRISON J. L. FRANK.
